UNITED STATES PATENT OFFICE.

ALBERT H. OVERMAN, OF SPRINGFIELD, MASSACHUSETTS, ASSIGNOR TO
THE OVERMAN WHEEL COMPANY, OF HARTFORD, CONNECTICUT.

CYCLE-LAMP.

SPECIFICATION forming part of Letters Patent No. 480,210, dated August 2, 1892.

Application filed September 1, 1890. Serial No. 363,616. (No model.)

To all whom it may concern:

Be it known that I, ALBERT H. OVERMAN, of Springfield, in the county of Hampden and State of Massachusetts, have invented new Im-

5 provements in Cycle-Lamps and Suspension Devices Therefor; and I do hereby declare the following, when taken in connection with accompanying drawings and the letters of reference marked thereon, to be a full, clear, and 10 exact description of the same, and which said drawings constitute part of this specification, and represent, in—

Figure 1, a rear view in perspective of a lamp and suspension device constructed in 15 accordance with my invention and shown as applied to a steering-head, which may be that of a Safety bicycle or of a tricycle; Fig. 2, a similar front view of the lamp and suspension device with the bowed glass removed.

20 Fig. 3 is an inside perspective view of the lamp, which is therein cut in two on the line *a b* of Fig. 2. Fig. 4 is a view of the lamp in transverse section on line *c d* of Fig. 2. Fig. 5 is a similar view showing one way

25 how the external contour of the lamp may be modified. Fig. 6 is a rear view in perspective showing the lamp-fount detached and adapted to direct draft instead of indirect draft, as is provided for in the lamp shown

30 by the preceding figures. Fig. 7 is a view in transverse section corresponding to Figs. 4 and 5 and showing a lamp adapted to direct draft and having the back of its body portion shaped to form its reflector. Fig. 8 is a

35 detached view in transverse section of the clamp of the suspension device shown by Figs. 1 and 2.

My invention relates to an improvement in cycle-lamps and suspension devices therefor,

40 the object being to produce a lamp of simple, compact, and cheap construction adapted to carry, in proportion to its size, a large quantity of oil and to keep the same at a low and uniform temperature and so insure a steady 45 combustion and good light.

A further object of the invention is to provide a simple suspension device which will securely support the lamp and cushion it against the vibration of the machine.

50 With these ends in view my invention consists in a cycle-lamp and a suspension device

therefor having certain details of construction and combinations of parts, as will be hereinafter described, and pointed out in the claims.

Under my invention the fount *A*, the combustion-chamber *B*, and the hood *C* of the lamp have continuous exterior lines and form divisions of the body portion of the lamp, the said body portion being oblong in form, substantially uniform in transverse section, and consisting of a number of suitable plates permanently secured together by riveting, brazing, or otherwise. This forms a very simple and compact construction in which the oil-fount has greater capacity in proportion to the size of the lamp than it can have in constructions in which it is made independent of the lamp-body and inserted thereinto. The fount is also directly exposed to the air 65 and is therefore kept cool and a steady and uniform combustion secured, whereas inclosed founts gradually heat and cause an unequal burning of the flame.

By making the hood *C* of the same transverse section as the fount *A* and the combustion-chamber *B*, I secure not only an ample and steady draft, but also a construction especially well adapted to the use for which the lamp is designed, as it has the strength and 75 stability pertaining to simple integral structures, affords the least opportunity to catch and hold dirt, will not rattle, reduces the wind-resistance to the minimum, and by its compactness and its smoothness escapes as 80 far as may be the heavy wear and mishaps of cycle-riding. The said fount is provided with a filling-cap *D* and burner *E* of any approved construction, the latter being provided with an ordinary horizontal wick-adjusting spindle 85 *F*, which projects outward through a horizontal slot *F'*, formed in one of the side walls of the combustion-chamber *B*, before mentioned. Preferably the front and side edges of the fount are provided with an oil-retaining flange 90 *G*, as shown by Figs. 3 and 6 of the drawings, this flange holding any oil which might be spilled in replenishing the fount or which might draw up therefrom. An opening formed 95 in the combustion-chamber and extending 100 between the forward edges of the fount and hood is inclosed by a single bowed plate of

glass H, curved to conform to the general form of the lamp and mounted in a light metal frame H', adapted to be hinged at one edge to the said combustion-chamber B, as at H², 5 and at the other edge to be fastened thereto, as at H³. This bowed glass takes the place of the lens and the two side lights ordinarily employed in cycle-lamps.

The reflector I, which is of ordinary construction, is set into an upright partition J, mounted in the rear portion of the combustion-chamber and located in the plane of the edges of the reflector which it is cut away to receive, its upper edge meeting the lower face 15 of the horizontal centrally-perforated flat diaphragm K, which forms the upper wall of the said combustion-chamber, its side edges joining the side walls of the said chamber and its lower edges being terminated above the 20 top of the fount, so as to form an opening under them and under the reflector for the draft of air which flows down behind the said partition and reflector, which, together with the rear wall of the chamber, form a flue for it, 25 the air being taken in through fine perforations B', formed in the said rear wall at a point about in line with the upper edges of the reflector and partition. A draft-guard M, secured to the upper face of the diaphragm 30 K, near the ends thereof, arches over the central perforation K', formed therein, and extends in line with the length of the hood and hence at a right angle to the curve thereof. It is made enough narrower in width and 35 enough lower in its arch than the hood to permit the draft of the lamp to draw over its edges and top, and to increase the draft openings M' M' are formed in its edges virtually in line with the openings C' C' formed in the 40 ends of the hood. Under the provisions of the above-described construction the draft will enter the perforations B' and flow down back of the partition J and the reflector I, issuing to the flame under the edges thereof. 45 The draft will then be upward through the combustion-chamber L, thence through the perforation K' of the diaphragm K into the hood, where it will be deflected by the draft-guard, and finally issue through the openings 50 C' C' at the ends of the hood.

If desired to employ a direct instead of an indirect draft, two upright tubes N N, open at both ends, may be set into the fount, as shown by Fig. 6 of the drawings, and take air at their lower ends, which open into a chamber N', formed by a false bottom N², of sheet metal, extending below the bottom of the oil-fount.

Fig. 4 is designed to show the general form in transverse section of the lamp shown in the preceding figures. This form may, however, be varied to have square corners, or its corners may be made still rounder, as shown by Fig. 5. In case the lamp is adapted to indirect draft, the back of its body portion may be shaped to itself form the reflector, as shown by N³ in Fig. 7, and the back flue dispensed

with, or a reflector might be attached directly to the back of the body portion of the lamp, which in the said figure is rounder in transverse section than any of the lamps shown by the preceding figures. 70

As shown in Figs. 1 and 2, the suspension device is composed of two arms O O, flat in transverse section, bowed longitudinally and outwardly, and respectively attached midway of their ends to the inner face of the flexible shell O' of a clamp having a rubber lining O² and a binding-screw O³ and adapted to receive a bent loop O⁴, having its ends secured 80 to a clip O⁵, embracing the steering-head O⁶, which may be that of a tricycle or of a Safety bicycle. Four spiral springs P connect the sides of the lamp above and below the center thereof with the ends of the arms O, which 85 spread considerably more than the width of the lamp, so that the same is hung between them and cushioned against shocks from any quarter, the springs being opposed in tension. The corresponding arms O⁷ O⁷ (shown in section by Fig. 9 of the drawings) are made of wire rods and are round in cross-section. If desired, the arms, whatever their construction and shape may be, may be made sufficiently resilient to supplement the cushioning 90 action of the spiral springs. 95

As shown by Fig. 7 of the drawings, the suspension device consists of four parallel spring-rods Q Q Q Q, arranged in two pairs and having their inner ends mounted in a 100 clamp Q', which may be of any approved construction. Each of these rods is coiled midway of its length and bent at its outer end to form a hook, the hooks of the respective pairs of rods being inserted into the opposite 105 ends of loops Q² Q², one of which is attached to the top and the other to the bottom of the lamp, which is thus suspended between four springs arranged in two pairs opposed in tension. 110

It will be apparent from the foregoing that in carrying out my invention some changes from the exact forms herein shown and described may be made. I would therefore have it understood that I do not limit myself to 115 such forms, but hold myself at liberty to make such changes and alterations as fairly fall within the spirit and scope of my invention.

Having fully described my invention, what 120 I claim as new, and desire to secure by Letters Patent, is—

1. A cycle-lamp having parallel sides and containing an exposed fount, a combustion-chamber, and a hood, all forming divisions 125 of the same body portion, a reflector located in the said chamber, means for supplying a draft of air thereto, a horizontal diaphragm separating the combustion-chamber from the hood, and a bowed glass constructed to extend across the front and partially around the sides of the combustion-chamber, which is thereto appropriately formed, substantially 130 as set forth.

2. A cycle-lamp having continuous exterior lines and containing an exposed fount, a combustion-chamber, and a hood, all forming divisions of the same body portion, an upright partition located in the rear portion of the combustion-chamber, a reflector set into the said partition and forming therewith a draft-flue supplying air to the combustion-chamber, a diaphragm separating the combustion-chamber from the hood and constructed with an opening into the latter, which is ventilated, and a bowed glass extending across the front and partially around the sides of the combustion-chamber, which is thereto appropriately formed, and conforming to the upright lines of the lamp, substantially as described. 40
- 10 combustion-chamber from the hood and constructed with an opening into the latter, and a bowed glass extending across the front and partially around the sides of the combustion-chamber, which is thereto appropriately constructed, substantially as set forth. 45
- 15 3. A cycle-lamp having parallel sides and containing an exposed fount, a combustion-chamber, and a hood, all forming divisions of the same body portion, a reflector located in the said chamber, means supplying a draft of air thereto, a horizontal diaphragm separating the combustion-chamber from the hood, a bowed glass constructed to extend across the front and partially around the sides of the combustion-chamber, which is thereto appropriately formed, and an upright flange located upon the edges of the upper face of the fount and within the exterior lines of the body portion of the lamp, substantially as set forth. 50
- 20 25 30 35 40 45 50 55 60 65 70
4. A cycle-lamp having continuous exterior lines of substantially uniform cross-section and containing an exposed fount, a combustion-chamber, and a hood, all forming divisions of the same body portion, an upright partition located in the rear portion of the combustion-chamber, a reflector set into this partition and co-operating therewith to form a draft-flue supplying air to the combustion-chamber, a diaphragm separating the combustion-chamber from the hood and constructed with an opening into the latter, which is ventilated, and a bowed glass extending across the front and partially around the sides of the combustion-chamber, which is thereto appropriately formed, and conforming to the upright lines of the lamp, substantially as described. 40
5. The combination, with a cycle-lamp, of a suspension device comprising four springs attached to the lamp on opposite sides thereof and diverging therefrom in radial lines, and means located on opposite sides of the lamp for supporting the outer ends of the said springs and sufficiently separated from the lamp for the radial interposition of the springs between them and it, substantially as set forth, and whereby the lamp is permitted to move in any direction under the control of the springs, which are opposed to each other in tension. 50
6. The combination, with a cycle-lamp, of a suspension device comprising two longitudinally-bowed carriers, four radially-arranged and tensionally-opposed springs respectively secured to the ends of the said carriers and to the lamp, and means for attaching the said carriers to a vehicle-frame, substantially as described. 60
- In testimony whereof I have signed this specification in the presence of two subscribing witnesses. 70
